UNITED STATES PATENT OFFICE.

RUDOLF F. GOECKE, OF ELYRIA, OHIO.

KETTLE.

1,241,619.

Specification of Letters Patent.

Patented Oct. 2, 1917.

Application filed March 24, 1917. Serial No. 157,083.

To all whom it may concern:

Be it known that I, RUDOLF F. GOECKE, a citizen of the United States, residing at Elyria, in the county of Lorain and State 5 of Ohio, have invented certain new and useful Improvements in Kettles; and I do hereby declare the following to be a full, clear, and exact description of the invention, such as will enable others skilled in the art to 10 which it appertains to make and use the same.

My invention relates to improvements in kettles and more particularly to kettles which are enameled, and which are frequently made of cast iron.

One of the objects of my invention is to provide means for connecting the kettle to the jacket, without placing undue strain upon the enamel or the enameled portion of 20 the kettle, thereby avoiding cracking or breaking the same.

This and other objects of my invention and the invention itself will be better understood from a descripton of an embodiment 25 of my invention.

Figure 1 is a section through a kettle and jacket showing an embodiment of my invention. Fig. 2 is an enlarged view of a detail of the embodiment shown in Fig. 1, 30 and Fig. 3 is a plan view of the embodiment shown in Fig. 1 with a half section taken along the line 3—3 in Fig. 1. Fig. 4 is a top plan view of the kettle.

Referring now to the drawing and to the 35 embodiment of my invention shown therein, at 4 is shown the jacket, which may be of any suitable shape, being shown in the embodiment as substantially hemispherical. Suitable supporting means, such as legs 5, 40 are provided for the jacket to support the same. Openings 6 and 7 are provided in the jacket wall, through which matter may enter or leave the jacket. At 8 is shown the kettle which may likewise be suitably 45 shaped, being here shown as substantially hemispherical. At 9 is shown the enamel on the inside of the kettle extending over the surface thereof and over the flange 10 on the edge of the kettle, as shown at 11.

50 At 15 is shown one portion of the means for connecting the kettle to the jacket. In the embodiment shown, the member 15 consists of a flange extending around the top edge 16 of the kettle. I prefer to make the 55 flange integral with the kettle and to secure the best results it is placed at some little dis-

tance below the flange 10. The jacket is provided with a flange 20 cut away on the inner edge at 21 to form a recess and a seat 22 for the means 15. Suitable packing 23 is 60 placed on the seat under the means 15, to seal the seam between the jacket and kettle and to soften the seat for the flange.

The flange 20 is provided with a threaded bore 25 for a bolt or screw 26, which extends 65 through an opening 28 in a clamp 29 provided with a heel 30 resting on one side of the flange 20 and with a toe 31 engaging the upper side of the flange 15. In the embodiment shown, a number of clamps 29 are employed, each engaging a portion of the flange 15. By using a plurality of clamps the strain on the flange 15 is so localized as to 70 eliminate entirely any danger of causing any strain upon the enamel.

75 Of course, it will be understood that the clamps 29 may be varied in length to suit each particular condition. For example, where the danger of injuring the enamel is increased, each clamp may be made smaller 80 and the number of clamps employed thereby increased, or, for rougher work, the clamps may be longer than illustrated, thereby reducing the number employed. If, in casting the kettle, the flange 15 is warped, or in any 85 other manner deformed, such unevenness can be taken care of by applying more or less pressure to the various clamps, avoiding the strain upon the kettle, which would result from the use of a continuous clamp endeav- 90 oring to press out the warp in the flange, and thereby placing strain on the kettle wall, which would inevitably crack or break the enamel. The seam between the flange 15 and the seat 22 may be made gas-tight. I prefer 95 to place the flange 15 far enough below the flange 10 to permit the ready removal of the clamps 29 and the bolts 26.

I have illustrated this embodiment and these particular details for the purpose of 100 better describing my invention. I do not wish to be limited to such embodiment or such details, as it will be apparent to those skilled in the art that numerous and extensive departures may be made from the form 105 and details of the embodiment shown without departing from the spirit of the invention.

I claim:—

110 1. In combination, a jacket provided with a flange about its mouth having an annular recess in the inner edge thereof forming

- a seat for a kettle flange, a kettle provided with an annular flange on the outside wall thereof and below the edge of the kettle, said flange fitting in said recess and resting 5 on said flange seat, a plurality of clamp members, each provided with a heel resting upon the jacket flange and a toe resting upon the kettle flange and means for drawing said clamps down upon said flanges to 10 hold said kettle and jacket together.
2. In combination, a jacket provided with a seat, a kettle and mechanism for fastening the kettle and jacket together, including means on the kettle resting on said seat and 15 a plurality of clamps for clamping said means in said seat and attaching means for attaching the clamp to the jacket.
3. In combination, a jacket and an enam- 20 elled kettle and mechanism for connecting the kettle to the jacket comprising an annular flange on the outside of the kettle wall and a plurality of clamps for clamping said flange to the kettle, said clamps extending all around the kettle and jacket and 25 means for fastening the clamps to the jacket.
4. In combination, a jacket and a kettle provided with an annular flange, clamping means for clamping the flange to the jacket, and devices for causing said means to exert 30 different pressures at different points about said flange.
5. In combination, a jacket and a kettle provided with means to be employed in connecting the kettle to the jacket and mechanism to apply to said means different pres- 35

sures at different parts of said means to connect said means to said jacket.

6. In combination, a jacket and an enam- 40 elled kettle provided with an annular flange on its outside wall, mechanism to apply to said flange different pressures at different parts of said flange to clamp said flange to said jacket.

7. In combination, a jacket provided with a flange about its edge, said flange having 45 an annular recess in the inner corner thereof forming a seat for a kettle flange, a kettle provided with an annular flange on the outside wall thereof and below the edge of the kettle, said flange fitting in said recess and resting on said flange seat, a plurality of clamp members, each provided with a heel resting upon the jacket flange and a toe resting upon the kettle flange and independent means for drawing each clamp 50 member down upon said flanges to hold said kettle and jacket together with different pressures on different parts of said flanges.

8. In combination, a jacket and an enam- 55 elled kettle, mechanism for connecting said jacket and kettle together with a gas-tight joint, comprising an annular member and a plurality of devices for clamping said member with different pressures at different points, and thereby connecting the kettle 60 and jacket together.

In witness whereof, I have hereunto signed my name this 16th day of March, 1917.

RUDOLF F. GOECKE.
